THILL COUPLING.

(Application filed Dec. 8, 1899. Renewed Mar. 7, 1901.)

(No Model.)

UNITED STATES PATENT OFFICE.

JAMES ALPHEUS GREEN, OF MILLDALE, VIRGINIA.

THILL-COUPING.

SPECIFICATION forming part of Letters Patent No. 683,854, dated October 1, 1901.

Application filed December 8, 1899. Renewed March 7, 1901. Serial No. 50,267. (No model.)

To all whom it may concern:

Be it known that I, JAMES ALPHEUS GREEN, a citizen of the United States, residing at Milldale, in the county of Warren and State 5 of Virginia, have invented certain new and useful Improvements in Thill-Couplings, of which the following is a specification.

For thill-couplings I have devised an improvement in which a tumbler is adapted to automatically effect its engagement by pressure with the clip-bolt and provide a safe and durable coupling easily and quickly disengaged for the removal of the shafts and to afford protection for the wear parts from dirt. 10 25 In the accompanying drawings, Figure 1 shows in section the coupling device of the shaft in coupled relation to the clip-bolt. Fig. 2 is a side view of the same. Fig. 3 is a cross-section on the line 3-3 of Fig. 1. Fig. 20 4 shows the under side of one of the shafts and the manner of securing the coupling-jaw thereto. Fig. 5 shows the jaw-iron in side view as secured to the shaft. Fig. 6 is the loop of the jaw-iron, and Fig. 7 shows the 25 tumbler in uncoupled position.

The axle has the usual clip-iron 2, the lugs 3 of the clip-iron, and the coupling-bolt 4, secured to the lugs.

To the under side of each shaft 5 is secured 30 a strap-iron 6, which I prefer to make integral with the coupling-jaw and to extend beyond the cross-bar and be secured thereto by a brace-arm, so as to give the shafts greater strength, as in Fig. 5. The jaw-forming end 35 7 of this strap extends below the end of the shaft and is made hollow and open at its under side from its coupling end to some distance up the shaft. The inner wall of the hollow forms a bearing part for the coupling-bolt, and the sides of the jaw have coincident 40 openings at this bearing which fit the coupling-bolt. The sides 8 of these openings flare and open at 9 at the under side of the jaw, whereby the latter is seated over and upon 45 the clip-bolt between the clip-lugs, as in Fig. 3. The coupling end of the jaw-iron projects approximately horizontally from the shaft in order that the side openings may be in vertical relation to the clip-bolt. The inner wall 50 of the jaw curves above the side openings to leave a space in the hollow for the working of the tumbler 10, which is mounted therein,

closely fitting its side walls and closing the under side of the hollow at said openings.

The tumbler is mounted on a pin 11 at the 55 outer side of and about on a horizontal line with the coupling-bolt, so that when closed within the hollow the tumbler will engage and have a bearing upon the clip-bolt and securely couple the jaw therewith. To provide this bearing, the tumbler has a recess 12 and is formed so that when engaged the lower part of the tumbler will close the side openings in the jaw. The lower part of the tumbler is made the heaviest end, so that when 60 the shafts are removed the tumblers will hang down at the outer sides of the jaw-openings, leaving them open and the jaws free to be set upon the coupling-bolts. The tumbler engages and bears upon the outer side of the 65 coupling-bolt and the jaw engages and bears upon its inner side, so that there is no draft force upon the tumbler-pin. The tumbler-recess above the coupling-bolt terminates in a nose projection 17, which when the tumbler 70 is open stands down across the jaw-openings, as in Fig. 7, and the tumbler is thereby rendered self-closing upon the coupling-bolt in placing and pressing the jaw-iron against the nose projection on the tumbler, which forces 75 80 it up to close the jaw-openings.

A plate 16 is bolted as a cover to the hollow of the jaw-iron, and within the hollow is secured a plate-spring 14, the free end of which projects so as to engage and hold the tumbler 85 closed. For this purpose the tumbler has a thumb part 13 slightly concave and the spring terminates in a convex bearing 15 and is caused to engage the thumb part with sufficient pressure to hold the tumbler firmly 90 closed upon the coupling-bolt.

Looking at Fig. 1, it is seen that the inner wall of the jaw, below the coupling-bolt, next the weighted end of the tumbler has a recess 16' within and between the side walls, so that 95 the weighted end of the tumbler while crossing and closing the jaw-opening is prevented from bearing upon the jaw and is held up with a firm seating upon the coupling-bolt.

To remove the shafts, the springs are pulled 100 out from off the tumbler thumb parts, and the lifting of the shafts will allow the tumblers to fall free of the clip-bolts and hang with their nose projections across the jaw side

openings, as in Fig. 7, so that in coupling the shafts the jaw-irons will in being set upon the coupling-bolts cause the thumb parts to press the springs out and pass under them, 5 and the tumblers will be thereby automatically locked with the clip-bolts. In this way the tumblers are automatically held in position for coupling and automatically held in position when coupled.

10 While the spring serves to hold the tumbler in locked position with the coupling-bolt, it also serves to hold the tumbler in open position, so that it can be only closed by forcing out the spring to pass under it and be there- 15 by engaged and locked, as shown in Fig. 1.

The axle-clip 2 is secured by the usual tie- 20 bar 18, Fig. 2, and this tie-bar is formed by a loop 19, which, with a loop 20 on the plate 16, serves to attach the safety-strap 21, which

25 hangs over the locking end of the spring.

The coupling parts as arranged and shown operate to effect the coupling by pressure upon the shafts in setting them upon the coupling-bolts.

25 I claim as my improvement—

1. In a thill-coupling and in combination with the shafts having jaw-irons formed with interior bearings open at their under sides to receive the clip-bolts, of weighted tumblers 30 pivoted to the jaws, each having a bolt-engaging recess terminating in an under bearing part adapted to close and uncover the jaw-openings and an overhanging nose part adapted to cross said jaw-openings below the 35 jaw-bearings when the tumbler is open, where- by the nose projections on being placed upon

the clip-bolts, will thereby force the tumblers in closed positions upon the clip-bolts, and means whereby the tumblers are locked.

2. In a thill-coupling, and in combination 40 with the shafts having jaw-irons formed with interior bearings open at their under sides to receive the clip-bolts, of weighted tumblers pivoted to the jaws, each having a bolt-engaging recess terminating in an under bearing part adapted to be closed upon the clip-bolts and an overhanging nose part adapted to cross the said jaw-openings below the jaw-bearings when the tumblers are open, and means for locking the tumblers consisting of 45 plate-springs on the under sides of the shafts and projections on the tumblers engaging said springs whereby in applying the shafts to the clip-bolts the tumblers are automatically closed and locked upon the bolts. 50

3. In a thill-coupling and in combination with the axle-clip, having the coupling-bolt, and the clip tie-bar having a loop, of the shaft jaw-irons, each hollow and having side openings terminating in bearings, a tumbler pivotally mounted in each jaw for engagement with the coupling-bolt, a spring depending in the jaw-iron for engagement with the tumbler, a cover-plate for the jaw-iron having a loop, and a safety-strap connecting said loop 60 with the loop of the clip tie-bar. 65

In testimony whereof I affix my signature in presence of two witnesses.

JAMES ALPHEUS GREEN.
